SHIELD FOR THE BOTTOM EDGES OF
TROUSER LEGS

George W. Blank, Philadelphia, Pa.

Application July 24, 1945, Serial No. 606,737

3 Claims. (Cl. 2-232)

1

My invention relates to new and useful improvements in a shield for the bottom edge of a trousers leg and one of the objects thereof is to provide means to impede the wearing of the bottom of the leg material and to hinder the fraying of the edge of said material.

Another object of this invention is to provide a shield of the class mentioned comprised of a number of baffle members detachably secured to the inside of a trousers leg to contact a person's shoe and thereby prevent the shoe from engaging the fabric which has a tendency to wear out such fabric.

Another object of the invention is to provide a shield for the bottom edge of a trousers leg which shield includes a strip of leather or equivalent material imposed on the inside face of the trousers leg contiguous the bottom edge of said leg and removably held in place by a number of baffle members constituting fasteners.

Another object of the invention is to provide a baffle member consisting of a pair of bendable legs having a head superimposed thereon and including a crown of hard wax generally known as sealing wax.

A further object of the invention is to provide a baffle member having a resistance ring in the crown thereof.

A still further object of this invention is to provide a baffle member consisting of a washer having bendable legs fixed thereto and having a crown of hard wax in which is embedded a resistance ring of high wear resistant metal, said washer, crown and ring constituting a head.

With the above and other objects in view this invention consists of the details of construction and combination of elements hereinafter set forth and then designated by the claims.

In order that those skilled in the art to which this invention appertains may understand how to make and use the same I will describe its construction in detail, referring by numerals to the accompanying drawing forming a part hereof, in which:

Fig. 1 is a view of a portion of a trousers leg with the near side bottom edge turned up to illustrate one form of the invention.

Fig. 2 is a vertical sectional view thereof.

Fig. 3 is a bottom edge view of the same.

Fig. 4 is a fragmentary sectional view on the line 4-4 of Fig. 1.

Fig. 5 is a sectional elevation of one of the baffle members in an early stage of the formation thereof.

2

Fig. 6 is a similar view at a point when the crown is partially formed.

Fig. 7 is a side elevation of the completed baffle member.

Fig. 8 is a top plan view of the baffle member at the completion of the first stage of the formation.

Fig. 9 is a similar view of Fig. 5.

Fig. 10 is a sectional elevation of another form 10 of baffle member showing a different way of fixing the legs to the washer.

Fig. 11 is a similar view after the resistance ring has been attached.

Fig. 12 also is a similar view of the completed baffle member of the other formation.

Fig. 13 is a top plan view of the washer and legs of said other form of baffle member.

Fig. 14 is a face view of the leather strip showing the center crease and fastener holes.

20 In carrying out the invention as herein embodied 15 represents a leg of a pair of trousers having front and rear creases 16 and 17 respectively. The trousers leg 15 has an outwardly disposed folded back portion generally known as a cuff 18.

The shield may include a strip 19 of leather or equivalent material of suitable size and shape and is imposed on the inner face of the trousers leg contiguous the bottom edge of the latter and desirably with the lower edge of the strip flush with the bottom edge of the leg. One of these strips is placed in the region of either or both creases 16 and 17 and temporarily or removably held in position by a number of baffle members or fasteners 20, 21 which pass through holes 22 formed in the leather strip 19.

30 The material strip 19 has an indicator 23 midway the ends thereof and may be a crease, a mark or stitches of thread. By placing the indicator contiguous a crease in the trousers leg, the strip 19 will be properly positioned.

The baffle members 20, 21 can be used without the strip 19 and each one has a reinforced head to reduce to a minimum the wear incident to 40 striking against a person's shoe or hard objects over which a person walks.

First referring to one form of baffle member I will describe that shown in Figs. 5 to 9, inclusive, wherein 24 is a washer having two bendable 50 prongs 25 and 26 attached thereto. These prongs project through the hole in the washer and they have right angle fingers 27 that lie against a face of said washer and are fixed in place by solder 28 or equivalent attaching means. One 55 prong, as 25, is shorter than the other prong

to permit the long one to be pulled away from the short one without interfering with the latter when said prongs are to be bent, as will be presently described.

Next a light coating of hard wax 29, such as sealing wax, in a soft condition, is applied over the solder and the exposed area of the face of the washer to which the solder was applied. This may be done by touching the surface of fluid wax with the washer one or more times until a coating of desired thickness is obtained. While the wax is still soft the metal reinforcing ring 30 is applied by laying the ring in position or contacting said ring with the waxed washer with the latter in an inverted position.

Instead of attaching the reinforcing ring 30 by means of the wax, said ring can be soldered in place, either by the same solder used for securing the ring or some additional solder.

After the reinforcing ring 30 has been mounted, the head 31 of the baffle member is completed by applying whatever additional wax is required to build up the desired size of head such, for example, as one depicted in Fig. 7.

In the modified form of baffle member 24, Figs. 10 to 13, inclusive, the prongs 32 and 33 are made in one piece from a short length of material bent upon itself and having a loop 34 fashioned therefrom and positioned at right angles to the prongs. The prongs, one of which is shorter than the other, are projected through the hole in the washer 35 until the loop 34 engages said washer.

It is not necessary but if desired the loop can be soldered to the washer. Preferably a retaining cap 36 is imposed on said washer 35 to cover or enclose the loop 34 and the edge of said cap is clinched, crimped or turned over the periphery of the washer to fasten the aforementioned parts together.

A coating 37 of the wax is now applied to the outer surface of the cap 36, Fig. 11, and the reinforcing ring 38 applied to said coating of wax, the same as described in connection with the first mentioned form. Thereafter the head 39 is built up by applying the necessary additional wax by dipping the head end of the device in the wax several times.

When the baffle members of either form are used without the material strip 19, the prongs are inserted from the inside of the trousers leg, the cuff 18 is pulled back and the prongs then bent over in opposite directions to follow the general curvature of the trousers leg, as shown in Figs. 2 and 4. The cuff is then returned to its normal position which will hide the prongs, prevent them from being accidentally displaced and generally assist in holding them against any turning action.

As the baffle members are applied reasonable care should be used to see that the heads of said baffle members are in close proximity to the lower end or edge of the trousers leg. The baffle members may be attached to either or both the front and back of the trousers leg and will function to prevent the trousers fabric from striking against the wearer's shoe and thereby save the fabric

from undue wear or damage. Even after the heads of the baffle members have worn down considerably they will still function properly because the reinforcing rings will practically prevent further wear on the baffle members.

When the material strip 19 is used, it is placed on the inside of the trousers leg contiguous the bottom edge with the indicator 23 in alignment with a crease in said trousers leg. Then the prongs of the baffle members are inserted in the holes 22 in the material strip 19, if not already mounted in said holes, and projected through portions of the fabric of the trousers leg, and finally bent over, as previously set forth.

The baffle members, either when used by themselves or in conjunction with the material strip, can be readily and easily removed to permit laundering or cleaning and pressing of the trousers and can be replaced without trouble.

Of course I do not wish to be limited to the exact details of construction herein shown and described as these may be varied within the scope of the appended claims without departing from the spirit of my invention.

Having described my invention what I claim as new and useful is:

1. In a shield of the kind described, a baffle member to be detachably secured to a trousers leg and comprising a washer, a pair of bendable prongs projected through the hole in the washer, a cap secured to the washer for holding the prongs in place, a head of hard wax fixed to the cap, and a reinforcing ring embedded in said head.

35 2. A shield for the bottom edge of a trousers leg comprising a material strip for securement to the inner face of a trousers leg contiguous the bottom edge thereof in the region of a crease, said strip having holes therein, and baffle members including prongs projected through the holes and through the trousers fabric and bent over against said fabric, each baffle member also including a reinforced head of hard wax.

40 3. A shield of the kind described comprising a material strip imposed on the inner surface of a trousers leg, and baffle members including prongs projected through said strip and portions of the trousers leg, said baffle members further comprised of hard wax heads exposed along the inner face of the trousers leg to receive the impacts of 45 a person's shoe during walking movements.
